UNITED STATES PATENT OFFICE

159,232

COMBINED HOLDER FOR AN UMBRELLA
AND GLOVES OR THE LIKE

Victor Silson, New York, N. Y.

Application November 2, 1949, Serial No. 5,833

Term of patent 3½ years

(Cl. D87—2)

To all whom it may concern:

Be it known that I, Victor Silson, a citizen of the United States of America, residing in New York, county of New York, and State of New York, have invented a new, original, and ornamental Design for a Combined Holder for an Umbrella and Gloves or the like, of which the following is a specification, reference being had to the accompanying drawing, forming part thereof,

Fig. 1 is a top plan view of a combined holder for an umbrella and gloves or the like, showing my new design.

Fig. 2 is a side elevational view thereof.

I claim:

The ornamental design for a combined holder for an umbrella and gloves or the like, substantially as shown.

VICTOR SILSON.
